UNITED STATES PATENT OFFICE.

GEORGE CRAIG DAVIS, OF ATLANTA, GEORGIA, ASIGNOR TO DRAPER CORPORATION,
OF HOPEDALE, MASSACHUSETTS, A CORPORATION OF MAINE.

FILLING-END CLEARER.

Application filed May 14, 1926. Serial No. 109,039.

This invention relates to filling replenishing looms and more particularly to filling end clearers employed in such looms to withdraw the filling end from the shuttle on call 5 for replenishment to prevent the production of imperfect cloth.

It has heretofore been proposed to provide filling replenishing looms with filling end clearers in which a filling catcher has been 10 mounted in front of the lay, and the filling end clearer has been mounted upon the lay to pass frontwardly of the filling end catcher on beat-up movement of the lay to permit the discharged filling carrier to pass 15 between the catcher and clearer upon replenishment of filling.

In looms of this general character it sometimes happens that the filling carrier or bobbin itself may be caught between the filling 20 end catcher and the filling end clearer, and in such case a smash is liable to occur as the lay goes back after replenishment of filling.

One of the objects of the present invention is to provide a filling end catcher and a 25 filling end clearer wherein means are embodied to prevent a smash should the filling carrier or bobbin be caught between the filling end catcher and the filling end clearer as the lay goes back after replenishment of 30 filling.

In accordance with the present invention, the filling end catcher is mounted in front of the lay and the filling end clearer is mounted upon the lay to pass frontwardly 35 of the filling end catcher on beat-up movement of the lay, and so mounted upon the lay that should a filling carrier or bobbin be caught between the catcher and clearer, the latter may yield in the plane of movement of the lay as the latter goes back after 40 replenishment, to prevent the occurrence of a smash or breakage of parts.

The invention and new features thereof will best be made clear from the following 45 description and the accompanying drawings of one good form thereof.

In the drawings:

Fig. 1 is a perspective view at the filling 50 replenishing side of the loom showing the present invention associated therewith; and

Fig. 2 is a detail plan view showing the 55 relation of parts when a filling carrier or bobbin gets caught between the filling end catcher and filling end clearer as the lay goes back following replenishment of filling.

The loom illustrated in the accompanying drawing may be of the usual automatically filling replenishing type, comprising a frame 1 which supports at its replenishing side a hopper stand 2 provided with the rotary 60 hopper 3 which carries the usual series of fresh filling carriers 4 adapted to be successively presented above the lay when the latter is in transferring position.

The transferring mechanism comprises the 65 usual transfer arm 5 which is pivotally mounted upon a stud 6 carried by the hopper stand 2, said transferring arm being provided with a downward extension 7 upon which is pivoted a dog 8 adapted to engage 70 the usual bunter on the lay when filling replenishment is to be effected. The parts so far described are or may be of usual construction and further explanation thereof appears unnecessary. 75

In looms of the filling replenishing type it is usual to provide the shuttle box at the replenishing side of the loom with an opening or passageway for the passage of filling carriers on transfer, and in the present instance of the invention the shuttle box 9 is provided with such bottom opening, as indicated at 10, so that upon the action of the transferring mechanism the filling carrier or bobbin to be discharged from the hopper 80 85 may be ejected downwardly.

In accordance with the present invention, the filling end catcher is mounted upon the loom frame in front of the lay, and when the lay moves frontwardly the filling end catcher 90 takes a position back of the bottom opening in the shuttle box, so that the ejected filling carrier may pass frontwardly of the filling end catcher. In the present instance of the invention, the filling end catcher 11 is 95 mounted upon the stud or dead shaft 12 extending from the loom frame, and such filling end catcher is provided with a laterally extending arm 13 which may be provided with a series of teeth 14 for engagement of the filling end *a* extending from the shuttle to the ejected filling carrier or bobbin *b*, as indicated in Fig. 1.

The filling end catcher 11 is pivotally mounted for yielding movement towards 105 and from the front of the loom and to this end it is under the influence of a spring 15 which normally holds the filling end catcher in its initial position but permits the filling end catcher to yield either frontwardly or 110

2
rearwardly. In the present instance of the invention, the filling end catcher 11 is provided with a pin 16 at its lateral end portion, as indicated in Fig. 1, to prevent the filling end *a* from becoming disengaged over the end of the filling end catcher. The parts so far described with relation to the filling end catcher may be of substantially the same character and construction as more fully shown and explained in the patent to Edward S. Stimpson, No. 1,422,728, dated July 11, 1922.

15 Mounted upon the lay is the filling end clearer which on frontward movement of the lay passes frontwardly of the filling end catcher a sufficient distance to permit the ejected filling carrier or bobbin to pass between it and the filling end catcher, so that on backward movement of the lay following replenishment, the filling end may be given a backward bend about the filling end catcher as the filling end clearer recedes or moves backward with the lay.

20 The filling end clearer comprises an arm 17 carried by the lay, and as the lay moves frontwardly the filling end clearer passes below and closely adjacent to the laterally extending arm 13 of the filling end catcher so that should the discharged filling carrier or bobbin be ejected from the shuttle at such times, it will pass between the filling end catcher and filling end clearer and on backward movement of the lay the filling end *a* will be given a whip-like movement to withdraw it from the shuttle and shuttle box.

25 It sometimes happens, however, that a filling carrier or bobbin will get caught between the filling end catcher and filling end clearer, and one of the important features of 40 the present invention is to provide a construction which, under such conditions, will prevent the smash or breakage of parts.

30 In accordance with the present invention, therefore, the filling end clearer or arm 17 is mounted upon a pivotal support carried by the lay, the axis of which support is vertical with respect to the lay race, with the result that the filling end clearer may yield frontwardly in a plane parallel to the lay movement should a filling carrier or bobbin be caught between the catcher and clearer, and such frontward swinging movement of the filling end clearer in a plane parallel to lay movement, enables the filling end clearer to disengage the filling carrier or bobbin as the lay goes back after replenishment.

35 More specifically stated, the lay is provided with a bracket 18 which may be adjustably secured thereto by a bolt 19 passing through an elongated slot 20 formed in the bracket, and extending from the bracket is a lug 21 in which is secured the pin 22 constituting the axis of swinging movement of the clearer. The clearer or arm 17 is

40 mounted upon the pin 22 for swinging movement in the plane parallel to lay movement, and may be conveniently secured in position on the pin 22 by a head 23 formed on the pin 22.

45 The clearer or arm 17 is normally under the influence of a spring tending to maintain the clearer or arm 17 in its normal position. In the present instance of the invention, the pin 22 is secured to the lug 21 by 50 a cotter pin 24 and a spring 25 placed about the pin 22 has one secured to the lug 21 and the other end secured at 26 to the arm or clearer 17, the construction being such that the normal action of the spring 25 is to 55 maintain the clearer in its normal position, as indicated in Fig. 1.

60 If desired, a washer or sleeve 27 may be interposed between the hub portion of the clearer or arm 17 and the lug 21 in order 65 to protect the spring from foreign matter. The arm 17 is provided with a stop 28 which, under the action of the spring 25, normally rests against the face of the bracket 18, as indicated in Fig. 1. As hereinbefore noted, 70 the axial support for the movement of the swinging arm 17 is vertical with respect to the lay or lay race and consequently the swinging movement of the clearer or arm 75 17 is in the direction of lay movement, so that should a filling carrier or bobbin be caught between the filling end catcher and the filling end clearer after replenishment 80 of filling, the clearer or arm 17 may yield in the plane of lay movement as the lay goes 85 back, and finally be drawn across and freed from the filling carrier or bobbin to permit 90 the latter to drop when the lay has approached or is in its rear position.

95 The action of the parts in preventing a 100 smash is represented in detail in Fig. 2, wherein it will be noted that the lay is moving backwardly and the filling carrier or bobbin *b* has been caught between the filling 105 end catcher and the filling end clearer when the lay was in front position. As the lay continues its backward movement, as indicated by the arrow in Fig. 2, the filling end clearer or arm 17 will be drawn across and finally freed from the trapped filling carrier 110 or bobbin and thereby prevent a smash or 115 breaking of parts.

120 Since it is desirable that the filling end clearer shall pass closely to the lower edge portion of the laterally extending arm 13 125 of the filling end catcher as the lay moves frontwardly, the adjustment afforded by the elongated slot 20 in the bracket 18 and the bolt 19 provides means for effecting the desired relation of these parts.

130 It will also be obvious that when a filling carrier or bobbin has been trapped, as indicated in Fig. 2, and the lay moves backward to disengage the filling end clearer from the bobbin or filling carrier, the spring

25 will act upon the filling end clearer to give it a sudden backward or whip like action as it passes from the trapped filling carrier or bobbin, to thereby whip the thread 5 from the shuttle and shuttle box, and to insure such action the filling end clearer or arm 17 is provided with a series of teeth 29 which will engage the filling end leading from the discharged filling carrier as the 10 lay goes back and the filling end clearer is drawn across and freed from the filling carrier or bobbin.

What is claimed is:

1. In a filling replenishing loom, the combination of the lay provided with a shuttle box having an opening for the discharge of filling carriers, a filling end catcher yieldingly mounted in front of the lay, and a filling end clearer carried by the lay to 15 pass frontward of the filling end catcher on beat-up movement of the lay and yieldingly mounted to cause its free end to swing in a plane parallel to the lay movement to trip past and disengage the filling carrier to 20 prevent a smash should such filling carrier be caught between the filling end catcher and filling end clearer as the lay goes back.

2. In a filling replenishing loom, the combination of the lay provided with a shuttle box having an opening in its bottom for the discharge of filling carriers, a filling end catcher mounted in front of the lay, a filling end clearer carried by the lay to pass frontwardly beyond the filling end catcher on 25 beat-up movement of the lay, a pivotal support on the lay for the filling end clearer the axis of which is substantially at right angles to the race of the lay that the free end of the filling end clearer may swing 30 frontwardly in a plane parallel to the lay movement should a filling carrier or bobbin be caught between the filling end catcher and filling end clearer as the lay goes back to thereby prevent a smash.

3. In a filling replenishing loom, the combination of the lay provided with a shuttle

box having an opening in its bottom for the discharge of filling carriers, a filling end catcher mounted in front of the lay, a filling end clearer carried by the lay to pass frontwardly beyond the filling end catcher on beat-up movement of the lay, a pivotal support for the filling end clearer the axis of which is substantially at right angles to the race of the lay that the free end of the filling end clearer may swing frontwardly in a plane parallel to the lay movement and trip past a filling carrier to prevent a smash should a filling carrier or bobbin be caught 50 between the filling end catcher and filling end clearer as the lay goes back, and means acting yieldingly upon the filling end clearer to return it to initial position relative to the lay after the caught filling carrier or bobbin has been disengaged from the clearer 55 by backward movement of the lay.

4. In a filling replenishing loom, the combination of the lay having a shuttle box provided with an opening for the discharge of filling carriers and bobbins, a filling end catcher mounted for yielding movement towards and from the front of the loom, a filling end clearer carried by the lay and comprising an arm to pass frontward of the filling end catcher on beat up movement of the lay and bend the filling about the filling end catcher as the lay goes back, a pivotal support for said arm having its pivotal axis in a vertical plane relative to the lay, a spring normally acting upon the arm and 70 yieldable to permit the free end of the arm to swing frontwardly in a plane parallel to the lay movement should a filling carrier or bobbin be caught between the filling end catcher and filling end clearer as the lay 75 goes back to free the end of the clearer from the caught bobbin or filling carrier to prevent 80 breakage of parts.

In testimony whereof, I have signed my name to this specification.

GEORGE CRAIG DAVIS.
